PENCIL HOLDER

Filed Jan. 17, 1933

INVENTOR.
Edward Hogg.
BY
H. G. Manning
ATTORNEY.

UNITED STATES PATENT OFFICE

EDWARD HOGG, OF WATERBURY, CONNECTICUT

PENCIL HOLDER

Application filed January 17, 1933. Serial No. 652,181.

This invention relates to article holding devices, and more particularly to a pencil holder having a slidable connection with a ring, adapted to be worn on the index finger.

5 One object of this invention is to provide a combination pencil holder and finger ring which will hold the pencil in writing or erasing position and which will also allow said pencil to be moved out of the way at the back 10 of the writer's hand when not in use.

A further object is to provide a pencil holder of the above nature having a swiveled connection with said ring.

A further object is to provide a pencil holder 15 of the above nature which will be simple in construction, inexpensive to manufacture, easy to wear and manipulate, compact, ornamental in appearance, and very efficient and durable in use.

20 With these and other objects in view, there has been illustrated on the accompanying drawing, one form in which the invention may be conveniently embodied in practice.

In the drawing:

25 Figure 1 represents an enlarged perspective view of the pencil holder, the pencil being shown in dotted lines.

Figure 2 is a side view of the holder as it appears in use.

30 Figure 3 is an enlarged sectional view of the same, taken on a transverse plane perpendicular to the axis of the finger ring.

Figure 4 is a fragmentary transverse sectional view through the finger ring, the view being taken along the line 4—4 of Figure 3.

35 Figure 5 is an enlarged fragmentary sectional view of the pencil holder, showing the swiveled connection, the view being taken along the line 5—5 of Figure 3.

40 Figure 6 is a sectional view of the same, showing the pencil holder turned 90 degrees from its normal position.

45 Referring now to the drawing in which like reference numerals denote corresponding parts throughout the several views, the numeral 10 indicates an annular finger ring which is intended to be worn upon the index finger of the writer's hand. The side edges of the ring 10 are folded inwardly, parallel 50 to the body of said ring to form a pair of

opposed angular grooves 11 and 12 which serve as guideways for a slidable arcuate plate 13. The ring 10 is preferably split as shown at 14, the resiliency of the ring thus produced, permits it to conform to various sizes of index fingers. The arcuate plate 13 is prevented from slipping out through the opening at the split section 14 of the ring 10, by means of a pair of lateral integral lugs 15 and 16, outwardly bent from the extremities of said 60 split ring. (See Figure 3.)

In order to support a pencil 19, or other implement, in spaced relation from the split ring 10, an elongated post or shaft 17 is rigidly secured to the central portion of the sliding plate 13, and said post 17 carries upon its outer end a split elongated tubular pencil holder 18. The holder 18 is made of such a size as to resiliently grip the body of a pencil 19 at any position along the length 70 thereof. The outer extremity of the post 17 has an integral transverse elongated head 20 which is adapted to be seated within a similar shaped elongated socket 21 formed in the periphery of the holder 18. The 75 socket 21 is provided with a central aperture 22 through which the post 17 extends.

The head 20 is normally held within the depressed socket 21 by means of a helical spring 23 surrounding said shaft 17 between 80 the ring 10 and the holder 18. The spring 23 tends to force said holder 18 outwardly at all times, yet permitting it to twist with respect to said ring 10. In use, when the holder 18 is laterally swung at right angles to its normal position, the head 20 will ride out of its socket 21 and assume the position as shown in Figure 6.

If the pencil is accidentally or manually 90 displaced from its normal parallel relation with respect to the axis of the ring, the pencil 19 will be automatically swung back to its original position by the influence of the spring 23. The pencil may be displaced almost as much as 90 degrees and still be automatically returned to its original position. If swung more than 90 degrees, it will automatically swing to a position 180 degrees 95 from the starting point. 100

Operation

In operation, the pencil 19 will first be inserted in the holder 18, and the ring 10 slipped upon the index finger of the writer's hand. When it is desired to write with the pencil, the holder 18 and associated parts may be slipped around the ring 10 to a position where the pencil 19 may be comfortably grasped by the fingers. When the writer wishes to use the eraser, the pencil may be manually swung 180 degrees without removing the pencil from its holder. When the writer wishes to use his hand to pick up a sheet of paper or for other purposes, the holder may be swung to the position shown in Figure 2, allowing the free use of the fingers, and yet keeping the pencil readily accessible at all times.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention what is claimed as new and for which it is desired to secure Letters Patent is:

1. In a pencil holder, a finger ring having an outer channel, a sliding plate in said channel, a radial shaft having rigid connection with said plate, and clamping means supported on the end of said shaft for holding a pencil or other implement.
2. In a pencil holder, a finger ring having an outer channel, a sliding plate in said channel, a radial shaft having rigid connection with said plate, and clamping means swiveled on the end of said shaft for holding a pencil or other implement.
3. In a pencil holder, a split finger ring having an outer channel, an arcuate plate in said channel, and slidably longitudinally therein, a radial shaft having a rigid connection with said plate, and having an enlarged head on its outer end, and pencil clamping means swiveled upon said head.
4. In a pencil holder, a split finger ring having an outer channel, an arcuate plate slidably fitted in said channel, a radial shaft having rigid connection with said plate, and having an elongated head integral with its outer end, a split tubular pencil holder having an interiorly depressed elongated socket within which said head is adapted to be seated, and spring means tending to hold said head within said socket at all times.
5. In a pencil holder, a split finger ring having an outer channel, an arcuate plate slidably fitted in said channel, a radial shaft

having rigid connection with said plate, and having an elongated head integral with its outer end, a split tubular pencil holder having an interiorly depressed elongated socket within which said head is adapted to be seated, and a helical spring surrounding said shaft and tending to force said holder outwardly at all times.

6. In a pencil holder, a split finger ring having its opposite side edges bent back upon the body of said ring to form an outer peripheral T-shaped slot therein, an arcuate plate slidably fitted into said slot, said ring having a pair of stop lugs integral at its split ends to retain said plate in said slot, a radial shaft having rigid connection with said plate, said shaft having an elongated head on its outer end, a split tubular pencil holder having an interiorly depressed elongated socket within which said head is adapted to be seated, and a helical spring surrounding said shaft and pressing against said holder and ring, the position of said head and socket being such that the said spring serves to maintain said ring and holder normally with their axes parallel.

In testimony whereof, I have affixed my signature to this specification.

EDWARD HOGG.
